US00D447429B1

(12) **United States Design Patent** (10) Patent No.: **US D447,429 S**
(45) Date of Patent: ** *Sep. 4, 2001

(54) **REMOTE SENSOR TEMPERATURE CONTROLLER**

Primary Examiner—Antoine Duval Davis
(74) Attorney, Agent, or Firm—Robert B. Leonard

(75) Inventors: **James A. Odom**, Apple Valley;
Thomas Caesar Tinucci, Eden Prairie;
James Edward Erickson, Eagan, all of
MN (US)

(57) **CLAIM**

The ornamental design for a remote sensor temperature controller, as shown and described.

(73) Assignee: **Honeywell International Inc.**,
Morristown, NJ (US)

DESCRIPTION

(*) Notice: This patent is subject to a terminal disclaimer.

(**) Term: **14 Years**

(21) Appl. No.: **29/099,537**

(22) Filed: **Jan. 22, 1999**

(51) LOC (7) Cl. **10-04**

FIG. 1 is a perspective view of the controller as seen from the front, bottom and left sides.

(52) U.S. Cl. **D10/49**

FIG. 2 is a front elevation view of the controller of FIG. 1.

(58) Field of Search D10/49, 50; 165/260,
165/270; 236/16, 1 B, 1 EA, 1 EB, 46 R,
51; 62/175; 364/557

FIG. 3 is a right side elevation view of the controller of FIG. 1.

(56) **References Cited**

FIG. 4 is a top plan view of the controller of FIG. 1.

U.S. PATENT DOCUMENTS

FIG. 5 is a bottom plan view of the controller of FIG. 1; and,

D. 434,338 * 11/2000 Odom et al. D10/49
* cited by examiner

FIG. 6 is a rear elevation view of the controller of FIG. 1.

The right and left side elevation views of the controller are mirror images of one another. The back of the controller is plain and unadorned.
